(57) CLAIM

The ornamental design for a “writing instrument container,” as shown and described.

DESCRIPTION

FIG. 1 is a perspective view of a writing instrument container showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken line showing of a writing instrument, in FIGS. 1–6, is for illustrative purposes only and forms no part of the claimed design.
